UNITED STATES PATENT OFFICE.

SAMUEL S. ROGERS, OF ASSOTIN CITY, WASHINGTON TERRITORY.

PEN-HOLDER.

SPECIFICATION forming part of Letters Patent No. 341,350, dated May 4, 1886.

Application filed March 16, 1885. Renewed March 16, 1886. Serial No. 195,480. (No model.)

To all whom it may concern:

Be it known that I, SAMUEL S. ROGERS, of Assotin City, Assotin county, Washington Territory, have invented a new and Improved 5 Pen-Holder; and I do hereby declare the following to be a full, clear, and exact description of the same, reference being had to the accompanying drawings, forming a part of this specification, in which—

10 Figure 1 represents a perspective view of the hand of a writer in the act of using a pen-holder constructed according to my invention. Fig. 2 is a longitudinal section through the pen-holder. Fig. 3 is a transverse section taken on the line $x-x$ in Fig. 2. Fig. 4 is a transverse section taken on the line $y-y$ in Fig. 2. Fig. 5 is a transverse section taken on the line $z-z$ in Fig. 2. Figs. 6 and 7 show detail views, also in perspective, of two modifications 15 of the center spindle of the pen-holder.

This invention relates to pen-holders; and it consists in the detailed construction and combination of the parts hereinafter described, by which the pen-holder is attached to the hand 20 of the writer, so that it is always kept at one angle and in the correct position for using the pen for either plain or ornamental writing.

This invention also consists in the combination of the parts for holding and guiding the 25 pen-holder with a fountain or ink-reservoir contained within said pen-holder, and with the mechanism for regulating the supply of ink to the pen.

In the accompanying drawings similar letters of reference indicate corresponding parts 30 in all the figures.

C is the center spindle of the pen-holder, provided with the collar c at its lower end. The upper portion of this spindle is bent round, 35 forming the spring-bar c' , having a catch, c^2 , at the end of it.

c^3 is a nut for adjusting the tension of the spring-bar.

D is a tube which surrounds the center spindle, C. It is provided with a long slot, d , in one side of it, and with a collar, E, one side of which is cut away, as shown at e in Figs. 2 and 5, the remaining portion of the said collar forming a catch, with which the catch c^2 45 can engage.

F is a tube surrounding the tube D, and

provided with a stop, f , which works longitudinally in the slot d , and keeps the said tube D from turning round. The end f' of tube F is made tongue-shaped and bent upward, 55 so as to support that part of the pen which projects from the holder. A small screw, f^2 , is inserted through the tubes D and F, the use of which is to act as a stop to the collar on the end of the center spindle and prevent it from 60 coming apart from the rest of the pen-holder.

G is a tube which completely surrounds the tube F, so as to form a space, g , which forms the fountain or ink-reservoir of the pen.

g' is a stopper, which can be removed to fill 65 the fountain.

g^2 is a very small hole in the tube G, which is made slightly thicker round this hole, so as to bear against the inside surface of the pen.

H is a tube of rubber or other elastic mate- 70 rial. This surrounds the tube G and holds the pen in position over the hole g^2 .

I is a small lever of bent wire, hinged in the rubber tube H, and extending for a short distance between it and the tube F. The end of 75 this lever is bent at right angles to it, forming a short plunger, i , which works back and forth in a hole in the said tube F when the end of the lever is pressed downward and allowed to rise again by the elasticity of tube G. 80

I sometimes dispense with the use of tube D and secure the collar E directly to the end of tube F, which does not then require to have the stop f formed on it.

The ink contained in the fountain g is fed to 85 the pen through the hole g^2 by the movement of the nibs of the pen against the writing material. When the ink does not flow freely enough, it can be made to do so by pressing the lever I so as to make the plunger i work 90 back and forth in the hole in the fountain. When the catch c^2 is connected to the collar E, as shown in Fig. 2, the pen-holder is operated by and held between the fingers in the usual manner, so that the end of the center spindle 95 slides back and forth on the hook b , which serves as a guide. When the catch c^2 is disconnected from the collar E, the end of the center spindle is held stationary by the hook b , which is gripped by the tension of nut c^3 100 between the said spindle and the spring-bar c' . The pen-holder then slides back and forth

upon the center spindle, C, and is also free to revolve upon it in either direction, as required in the act of writing.

Fig. 6 shows a simple modification of the center spindle, which, in this case, is made of a wire bent double at K, upon which the pen-holder slides back and forth, and is provided with spring ends k k, which can be sprung over one of the fingers of the writer just above the knuckle-joint, to connect the same to the hand. In order to facilitate the removal of the ends from the finger, they are made with sloping portions k' k'. When the collar E is pressed upon these sloping portions, the ends k k are sprung apart and the finger is set free. l is a screw and thumb-nut for regulating the tension of the ends k k.

Fig. 7 shows another modification of the same device; but in this case one of the spring ends k' is hinged to the body of the instrument, to still further facilitate its attachment and detachment with the finger, and both ends are covered with rubber casings k'', to preserve the skin of the writer from injury.

Having thus described my invention, what I claim as new, and desire to secure by Letters Patent, is—

1. In a pen-holder, the combination, with a central spindle, of surrounding tubes, one having an end or projection resting against the under side of the outer portion of the pen and the other tubes adapted to receive between them the inner end of the pen, substantially as and for the purpose set forth.

2. In a pen-holder, the combination of a central spindle, the tube F, adapted to slide thereon, and provided with the end f', the collar E, the tube G, forming the fountain g, and having the small hole g' therein, and the rubber tube H, for holding the pen, substantially

as described and shown, and for the purpose set forth.

3. In a pen-holder, the combination of the tube F, adapted to slide back and forth upon a central spindle, and provided with the end f', the tube G, forming the fountain g, and having the small hole g' therein, the rubber tube H, for holding the pen, and the lever I, the end i of which forms a short plunger, substantially as shown and described.

4. In a pen-holder, the combination of a device, substantially as described, for the connection of the pen-holder to the finger, and the pen-holder having a sliding or extensible connection with said device, whereby the holder and finger are adapted to have the required relative movements in the operation of writing, substantially as set forth.

5. In a pen-holder, the combination of a central spindle having spring ends k k and sloping portions k' k', the tube F, adapted to slide back and forth upon the said central spindle, and provided with the end f', the collar E, the tube G, forming the fountain g, and having the small hole g' therein, and the rubber tube H, for holding the pen, substantially as shown and described.

6. In a pen-holder, the combination of a central spindle, the tube D, having the slot d, and adapted to slide back and forth upon the said central spindle, the tube F, provided with the end f' and the stop f, the collar E, the tube G, forming the fountain g, and having the small hole g' therein, and the rubber tube H, for holding the pen, substantially as shown and described.
